UNITED STATES PATENT OFFICE

THOMAS W. AINLAY, OF DENVER, COLORADO

ORE SEPARATOR

Application filed January 16, 1931. Serial No. 509,175.

This invention relates to an ore separator and has for its principal object the provision of a highly efficient machine for this purpose which will employ centrifugal force to cause a classification and separation of the ore according to the specific gravity of its various mineral constituents. The machine relates more particularly to the type of separator employing a rotating bowl for imparting the centrifugal effect to the ore.

It has been found that in separators of this character the design of the bowl riffle is highly important. Riffles differing minutely in design and angularly have been found to give vastly different percentages of recovery on a given ore. The principal object of this invention is to provide a riffle design in a centrifugal bowl separator which will give a maximum recovery.

Another object of this invention is to provide means in a centrifugal ore separator which will prevent black sand, gangue, etc., from packing in the riffles so as to constantly maintain a maximum riffle area active for the reception of the gold and other valuable minerals.

A further object of the invention is to provide adjustable means in a centrifugal bowl ore separator for deflecting a portion of the water from adjacent the periphery of the bowl into the vortex at the center so that this water will be constantly reused and will not overflow. This feature becomes invaluable in arid regions. The deflector also serves as a baffle to create eddy currents in the solution adjacent the riffles so as to prevent sand from packing therein.

A still further object is to provide a renewable bowl liner for a centrifugal bowl ore separator. The liner is preferably molded from tough rubber. Such a liner will wear from three to four times longer than a metallic bowl; will reduce the weight of the entire machine so as to economize both on horsepower and transportation charges; and will greatly reduce the cost of manufacture. It removes the necessity for machining the riffles in the bowl since they can be molded directly into the rubber lining with the assurance that the riffles of every machine will be exact

duplicates with the riffles of every other machine. It also allows the entire bowl to be quickly and easily relined, should the riffles become too badly worn for efficient use, without discarding or dismantling the remainder of the machine.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a side elevation partially in section of one arrangement of the improved ore separator.

Fig. 2 is an enlarged cross section of the bowl liner.

Fig. 3 is a plan view of the bowl employed in the improved ore separator with the liner in place therein.

Fig. 4 is an enlarged detail section through the edge of the bowl illustrating a method for maintaining the liner in place therein.

Fig. 5 is a structural diagram illustrating in detail the various angles of the bowl riffles.

Fig. 6 is a diagrammatic view illustrating the action of the deflector when the bowl is in use.

Fig. 7 is a detail perspective view of the deflector.

As illustrated, the machine comprises three vertically superimposed centrifugal bowls 10, 11, and 12 mounted in a suitable supporting frame 9. This is simply illustrative of an arrangement of the machine and it is desired to be understood that it could be constructed with but a single bowl. The bowls 10, 11, and 12 are keyed or otherwise secured upon a vertical central shaft 13, which passes through hubs 14 formed upon the bowls.

The shaft 13 is suspended in thrust bearings 40 adjacent its upper extremity and may be braced at the bottom by means of an additional bearing 15. The shaft 13 may be

driven in any desired manner such as through the medium of a bevel gear 16 secured at its upper extremity.

The bowls 10, 11, and 12 are similar to each other and semispherical in shape. As illustrated the bowls are provided with an inner liner consisting of a series of rubber, lining segments 17. The inner faces of the lining segment 17 are molded with a series of horizontal angular grooves forming riffles 18. The lining segments 17 may be held in place in the bowls in any desired manner. The segments could be provided with attachment bolts 19 cast therein so that they would project through openings in the bowls.

It is preferred to provide an angular retaining bar 20 about the top of the bowl to hold the lining in place. This bar may be formed in a complete circle if desired. It is preferred, however, to form it in two sections, as illustrated in Fig. 3, so as to facilitate its attachment and removal when the bowl in place in the machine.

The riffles 17 could, of course, be formed directly in the face of the bowls if desired so that the pulp would contact directly with the bowl, as indicated in Fig. 6, and the liners eliminated. The liners, however, have many advantages as before noted herein.

The machine is fed from a feed chute 21. The feed chute 21 terminates in a central sleeve 22 which surrounds the shaft 13 and opens to the interior of the bowl 10 adjacent the bottom thereof. The overflow from the bowl 10 is received in a surrounding hopper 23 which terminates in a second similar feed sleeve 24 which opens adjacent the bottom of the bowl 11. The overflow from the bowl 11 is received in a second hopper 25 which terminates in a third similar feed sleeve 26 which in turn opens adjacent the bottom of the bowl 12. The overflow from the bowl 12 is received in a circular launder 27 and flows from a discharge spout 28 which discharges to the dump or to a second treatment. Any leakage between the bowl 12 and the launder 27 is received on a circular bearing protector 29 which throws it away from, and protects the bearing 15.

Each of the bowls 10, 11, and 12 is provided with a cleanup plug 30 and each of the hoppers 23 and 25 are provided with a second plug 31 which allows access to the plug 30.

A blade-like deflector 32 projects downwardly into each of the bowls. The deflectors 32 may be supported in any desired manner provided the support allows universal adjustment. As illustrated, each deflector is pivoted upon one leg of an angle clip 33 by means of a pivot bolt 34. The angle clip 33 is adjustably secured upon a bracket 35 by means of a clamp bolt 36 which passes through a slotted opening 37 in the angle clip 33. The bracket 35 is secured to the sup-

porting frame 9 by means of attachment screws 38 which pass through a slotted opening 39 in the bracket so as to allow horizontal adjustment thereof.

The above described supporting means allows universal adjustment of the deflector 32. It can be set at any desired horizontal angle to the interior surface of the bowl by adjusting the pivot bolt 34. It can be adjusted to any desired distance from the interior surface of the bowl, by adjustment of the attachment screws 38. Its vertical placement and vertical angle can be adjusted by means of the clamp bolt 36.

In use, a wet ore pulp solution is fed to the machine through the feed chute 21 from a screen, feeder, crusher or other preceding machine. The feed chute 21 and the sleeve 22 deposit the pulp in the bottom of the bowl 10. The bowl is rotated so as to cause the solution to travel outwardly and upwardly over the interior surface of the liner 17 and across the riffles 18.

The rotation of the bowl creates a centrifugal force which acts upon the solution and its contained solids causing the heavy desirable mineral particles to be forced further outwardly than the lighter particles. This causes the minerals to pass into and be retained in the grooves of the riffles 18. The remaining solution overflows at the top of the bowl 10 into the hopper 23 which will deposit it, through the sleeve 24, at the bottom of the second bowl 11.

The action of the second bowl 11 is similar to that of the first bowl 10 and it will act to recover any mineral escaping in the overflow from the bowl 10. The overflow from the bowl 11 is in turn similarly deposited in the bowl 12 which acts as a clean-up bowl to remove any remaining mineral that may have escaped the action of the bowls 10 and 11.

At the end of a run, or as often as necessary the recovered metal or mineral can be washed from the riffle grooves by means of a suitable hose and allowed to discharge through discharge openings closed by the plugs 30.

It can be seen that in many instances a single bowl will be all that will be necessary and it will also be seen that any number of bowls can be mounted in tandem, as ore conditions indicate.

The deflector 32 is very important. First it acts as a baffle to break the smooth quiescent flow of the pulp solution upwardly over the bowl sides so as to cause agitation and eddy currents in the solution as shown at "A", Fig. 6. These eddy currents act to agitate and wash the valueless and comparatively light sands from the riffle so as to prevent packing of the riffles with sand and valueless material.

The deflector, however, serves still another important purpose. If it is set at an inwardly diverging angle to the path of rotation it will act to skim off the water and thin solu-

tion from the surface of the rapidly revolving wall of solution and direct this water back into the center of the bowl against the feed sleeve 22 as shown at "B" in diagram in Fig. 5. 6. This returned water will again fall to the bottom of the bowl and travel upwardly over the riffles. This acts to constantly reuse a portion of the solution water in each bowl so as to greatly reduce the amount of water over 10 flowing from the bowl and the wasteage of water in the plant.

As before stated the exact angular placement of the walls of the riffles 18 is very important. A great many experiments have 15 been made with these riffles cut at various angles and it has been found that the most efficient results are obtained with the riffles cut as shown in the drawings and more particularly as shown in the diagram of Fig. 5. In 20 Fig. 5 a vertical section of one half of the bowl liner is illustrated in diagram. The bowl surface is spherical with its center indicated at "C".

Let us assume that typical radial lines R , 25 R^1 , and R^2 are drawn from the center C through the points P , P^1 , and P^2 of typical riffles and that the groove walls below each of these riffles is extended outwardly as shown by the lines D , D^1 and D^2 . Now let us draw 30 horizontal chords through the riffle points P , P^1 , P^2 and extend these outwardly as shown by the lines E , E^1 , and E^2 .

Now let us study the resulting diagram. It will be noted that acute angles are formed 35 by the lines DPR , $D^1P^1R^1$, and $D^2P^2R^2$ which are indicated on the diagram at α , α^1 , and α^2 , respectively. It will also be noted that the angles α , α^1 and α^2 increase as the bottom of the bowl is approached. This gradual increase of angle from the radial lines is carried 40 proportionately throughout all of the riffles in the bowl. It will also be noted that the angles formed by the lines $E^2P^2D^2$ and $E^1P^1D^1$ shown at γ^2 and γ^1 , respectively, lie 45 below the chord lines and decrease as the top of the bowl is approached until a plane is reached approximately $\frac{2}{3}$ of the depth above the bottom when the line PD will lie upon the line PE as indicated at $z-z$. In other 50 words, at this plane the top wall of the riffle groove will lie directly upon a horizontal chord. Above this plane the angle DPE begins to increase above the chord as shown at y .

55 Another way to observe the angles of the riffle grooves is to picture the wall of each groove continued to the center of the bowl. Each would then form an imaginary cone with its apex at the center (see F) and with 60 the groove wall for its base. The incline of each of these cones would decrease as the top was approached until the plane $z-z$ was reached when the cone would disappear above this plane. The cone angles would begin to increase but the cones would be invert-

ed as shown by the dash-dot lines of Fig. 5.

As before stated, careful experiment has shown that unless the riffle grooves are cut at least approximately conforming to the above geometric angles maximum results can not 70 be obtained.

While a specific form of the improvement has been described and illustrated herein, it is desired to be understood that the same may be varied, within the scope of the appended 75 claims, without departing from the spirit of the invention.

Having thus described the invention, what is claimed and desired secured by Letters Patent is:—

1. A bowl construction for centrifugal ore separators comprising: a bowl, the inner surface of which conforms substantially to a portion of a sphere; a series of horizontal, adjacent, V-shaped grooves in said inner surface, the upper wall of one of said grooves lying substantially in a horizontal plane; and the upper walls of the grooves below said one groove being inclined outwardly and downwardly from a horizontal plane. 80 85 90

2. A bowl construction for centrifugal ore separators comprising: a bowl, the inner surface of which conforms substantially to a portion of a sphere; a series of horizontal, adjacent, V-shaped grooves in said inner surface, the upper wall of one of said grooves lying substantially in a horizontal plane, the upper walls of the grooves above said one groove being inclined outwardly and upwardly from a horizontal plane and the upper walls of the grooves below said one groove being inclined outwardly and downwardly from a horizontal plane. 95 100

3. A bowl construction for centrifugal ore separators comprising: a bowl, the inner surface of which conforms substantially to a portion of a sphere; a series of horizontal, adjacent, V-shaped grooves in said inner surface, the upper wall of one of said grooves lying substantially in a horizontal plane, the upper walls of the grooves above said one groove being inclined outwardly and upwardly from a horizontal plane and the upper walls of the grooves below said one groove being inclined outwardly and downwardly from a horizontal plane, the incline of the latter walls gradually increasing in angle as the bottom of the bowl is approached. 110 115 120

4. An ore separator comprising: a rotatably mounted bowl having a vertical series of horizontally placed, V-shaped grooves formed in its inner surface, the upper wall of each of said grooves forming a portion of an imaginary cone, all of said cones having their apexes at the vertical center line of said bowl and successively increasing in incline as the bottom of said bowl is approached. 125

In testimony whereof, I affix my signature.

THOMAS W. AINLAY. 130
